(57) CLAIM

The ornamental design for a positive airway pressure delivery console, as shown and described.

DESCRIPTION

FIG. 1 is a front perspective view of a positive airway pressure delivery console showing an embodiment according to our new ornamental design;

FIG. 2 is front view thereof;
FIG. 3 is a rear view thereof;
FIG. 4 is a top view thereof;
FIG. 5 is a bottom view thereof;
FIG. 6 is a right side view thereof;
FIG. 7 is a left side view thereof;
FIG. 8 is another front perspective view thereof;
FIG. 9 is a front perspective view of a positive airway pressure delivery console showing an embodiment according to our new ornamental design;
FIG. 10 is front view thereof;

FIG. 11 is a rear view thereof;
FIG. 12 is a top view thereof;
FIG. 13 is a bottom view thereof;
FIG. 14 is a right side view thereof;
FIG. 15 is a left side view thereof; and,
FIG. 16 is another front perspective view thereof.
The broken lines represent environment or structure and do not form a portion of the claimed design.
